COMBINATION CLUB AND FIREARM

Jesse M. Bohler, Atlanta, Ga.

Application May 16, 1939, Serial No. 274,023

3 Claims.

(Cl. 42—1)

The present invention relates to new and useful improvements in weapons for use particularly by police officers and has for its primary object to provide, in a manner as hereinafter set forth, 5 a device of this character in the form of a combination club, black jack or the like and firearm.

Another very important object of the invention is to provide, in a combination weapon of the aforementioned character comprising a spring 10 projected plunger for actuating a firing pin, novel means for releasably securing said plunger in cocked position.

Another very important object of the invention is to provide a combination weapon of the 15 character described comprising a construction and arrangement which is such that the device may be expeditiously loaded and the discharged shell removed.

Other objects of the invention are to provide 20 a combination weapon of the character set forth which will be comparatively simple in construction, strong, durable, highly efficient and reliable in use, compact and which may be manufactured at low cost.

25 All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a combination weapon constructed in accordance with the present invention, showing the device cocked and secured by the safety.

Figure 2 is a view in vertical longitudinal section through the device.

Figure 3 is a cross sectional view, taken substantially on the line 3—3 of Fig. 2.

40 Figure 4 is a cross sectional view, taken substantially on the line 4—4 of Fig. 2.

Figure 5 is a detail view, looking at the inner or rear end of the barrel.

45 Figure 6 is a view in side elevation of the barrel and head thereon, showing the rear end portion thereof broken away in section.

Figure 7 is a top plan view of an intermediate portion of the device, showing the trigger cocked 50 with the safety device in released or inoperative position, the guard being shown in horizontal section.

Figure 8 is a detail view in perspective of the firing pin.

55 Figure 9 is a perspective view of the instru-

ment through the medium of which the device is cocked.

Referring now to the drawings in detail, it will be seen that the embodiment of the invention which has been illustrated comprises a substantially tubular housing 1 of suitable metal. Formed longitudinally in the upper portion of the tubular housing 1 is a slot 2. A lateral notch or recess 3 communicates with the slot 2 at the rear end portion thereof.

10 Threadedly mounted in the forward end portion of the tubular housing 1 is a removable barrel 4. The rear portion of the barrel 4 has formed therein a recess 5 for the reception of a spring pressed latch 6 which is pivotally mounted on the forward end portion of the housing 1. The reference numeral 7 designates a cartridge which is mounted in the barrel 4. Threadedly mounted on the barrel 4 is a substantially bulbous removable head 8 which may be of any suitable 20 heavy material.

Also threadedly mounted in the forward portion of the tubular housing 1 is a block or plug 9. The block or plug 9, it will be observed, is spaced from the rear end of the barrel 4. Mounted in the tubular housing 1 immediately adjacent the rear of the block or plug 9 is a guide 10. The reference numeral 11 designates a firing pin which extends slidably through an opening provided therefor in the block or plug 9. The firing pin 11 includes a body or member 12 on its rear end which is slidable in the guide 10. The member 12 has formed therein a notch 13 having inclined end walls, as best seen in Fig. 8 of the drawings. The notch 13 accommodates the pointed end of the retaining screw 14 which is threadedly mounted in the guide 10 for limiting the movement of the firing pin 11.

25 Threadedly mounted in the rear end portion of the tubular housing 1 is a coupling 15. Anchored in the coupling 15 is a handle 16 in the form of a flexible steel cable having a head 17 on its rear end. Slidably mounted on the handle 16 is a ring 18 of suitable material, such as leather. Pivotally mounted on the ring 18 is a 30 wrist loop 19 which is also preferably of leather.

35 Mounted for longitudinal sliding movement in the tubular housing 1 is a plunger 20 which is adapted to actuate the firing pin 11. A coil spring 21 projects the plunger 20. The forward 40 end portion of the coupling 15 is socketed, as at 22, for the reception of the coil spring 21. Mounted on the plunger 20 and rising therefrom is a pin or trigger 23 which is operable in the slot 2 and engageable in the notch 3 for releasably 45

securing said plunger in cocked position. This is illustrated to advantage in Figures 2 and 4 of the drawings.

Pivottally mounted on the tubular housing 1 adjacent the rear end portion of the slot 2 and the notch 3 is a safety latch 24. The reference numeral 25 designates an operating bar for the safety latch 24 which is pivotally and slidably mounted on the tubular housing 1, said operating bar 25 being pivotally connected to one end of said safety latch 24, as at 26. The bar 25 has formed therein a longitudinal slot 27 which accommodates a securing screw 28. A roughened thumb button 29 is provided on the bar 25 for actuating same. The free end of the latch 24 is engageable with the trigger or pin 23 for positively securing same in the notch 3. A guard 30, which is substantially in the form of a forwardly tapering hood on the upper portion of the tubular housing 1, shields the trigger or pin 23, the safety device, etc. The rear portion of the guard 30 is open in a manner to accommodate the thumb of the hand which holds the device.

In Figure 9 of the drawings, the reference numeral 31 designates the bar which is used for cocking the plunger 20. Toward this end, the bar 31 is provided on one end with an enlarged eye 32 for the reception of the trigger or pin 23 for connecting said bar thereto. Loosely mounted on the other end of the bar 31 is a conventional key ring 33.

It is thought that the operation of the device will be readily apparent from a consideration of the foregoing. Briefly, the latch 6 is disengaged from the barrel 4 to permit said barrel to be removed from the housing 1 for the insertion of the cartridge 7 in the breech of said barrel. The barrel 4 with the cartridge 7 therein, is then threaded into the forward end portion of the housing 1. When the barrel is screwed home the latch 6 enters the recess 5 and locks said barrel. The plunger 20 is retracted against the tension of the coil spring 21 by connecting the rod 31 to the trigger or pin 23 and pulling same rearwardly in the slot 2 and then swinging said trigger or pin into the notch 3. The bar 25 is then moved rearwardly through the medium of the thumb button 29 for swinging the safety latch 24 from the position shown in Fig. 7 of the drawings to that illustrated in Fig. 1. Thus, the trigger or pin 23 is positively secured in cocked position in the notch 3. The construction and arrangement is such that the safety latch 24 moves past dead center when it is swung to operative position. By tightening or loosening the screw 28 the movement or action of the bar 25 may be regulated as desired. To fire the cartridge 7, the bar 25 is moved forwardly beneath the guard 30 through the medium of the thumb button 29 for swinging the safety latch 24 to the position shown in Fig. 7 of the drawings. After this has been done the trigger or pin 23 may still be conveniently held in the notch 3 with the thumb. Now, to fire the weapon it is only necessary to swing the trigger or pin 23 out of the notch 3 thus releasing the

plunger 20 and permitting the coil spring 21 to function by driving said plunger forwardly. The plunger 20 strikes the member 12 and drives the firing pin 11 forwardly against the rear end of the cartridge 7. By grasping the flexible handle 16 in an obvious manner the device may be conveniently used as a club, black jack or the like, the head 8 constituting the striking end. The wrist loop 19 prevents loss of the weapon, as will be readily understood. Also, this loop 19 is connected to the handle 16 in a manner to readily adjust itself thereon. Referring again to Fig. 2 of the drawings, it will be observed that the coupling 15 has formed therein openings for the reception of solder, as at 34, for anchoring the handle 16 therein.

It is believed that the many advantages of a combination weapon constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A weapon of the class described comprising a tubular housing, said housing having a longitudinal slot therein and further having a notch therein communicating with the slot at the rear end portion thereof, a removable barrel, for the reception of a cartridge, mounted on one end of the housing, a spring projected plunger operable in the housing, a firing pin in the housing operable by said plunger, a pin on said plunger operable in the slot and engageable in the notch for securing said plunger in cocked position, a safety latch pivotally mounted on the housing and engageable with the second named pin for securing same in the notch, and a manually operable bar pivotally and slidably mounted on the housing and pivotally connected to one end of said safety latch for actuating same.

2. A weapon of the class described comprising a substantially tubular housing, a barrel, for the reception of a cartridge, mounted on said housing, means for firing the cartridge, said means including a spring projected plunger slidably mounted in the housing, a pin mounted on said plunger for cocking same, a safety device mounted on the housing for releasably securing the pin in cocked position, and an inclined hood mounted on the housing and constituting a guard for shielding the pin and the safety device, said hood being open at its rear end for the reception of a thumb.

3. A weapon of the class described comprising a housing, a striking head on one end of said housing, a flexible handle on the other end of the housing, a head on one end of said flexible handle, a ring slidably mounted on the handle, and a flexible wrist loop having its end portions pivotally connected to the ring.
